(57) **CLAIM**

I claim the ornamental design for foodservice equipment, as shown and described.

DESCRIPTION

FIG. 1 is a perspective view of a foodservice equipment of the claimed design;

FIG. 2 is a front view thereof

FIG. 3 is a right side view thereof, the left side view is a mirror image of the right side view;

FIG. 4 is a top view thereof; and,

FIG. 5 is a bottom view thereof.

The broken lines in the drawings are for illustrative purposes only and form no part of the claimed design. The dash-dot lines shown in some of the drawings are provided to define the boundary of the claimed design and form no part of the claimed design.
